United States Patent Office.

JAMES FREDERICK TRAVIS, OF NEW YORK, N. Y., ASSIGNOR TO ARCHER, PANCOAST, AND COMPANY, OF SAME PLACE.

Design No. 3,124, dated July 21, 1868.

DESIGN FOR A GASALIER.

The Schedule referred to in these Letters Patent and making part of the same.

TO ALL WHOM IT MAY CONCERN:

Be it known that I, JAMES FREDERICK TRAVIS, of the city, county, and State of New York, have originated a new Design for Gasaliers, of which the following is a full, clear, and exact description, reference being had to the accompanying drawing, forming part of this specification.

The new and ornamental design for gasaliers or chandeliers, shown in the annexed drawing, consists of a central stem, A, of circular form in its transverse section, surrounded at or near its top with two inverted cones or conically-shaped protuberances, *a* and *b*, also, lower down, as at *c*, with a reversely-diminishing circular ornament, of step-like character, and with sundry beads or collars, terminating at its bottom in a polygonal-shaped swell or body, B, merging at its top into the stem, by two circular hollow tapering formations, as at *d* and *e*, and extended below by a reversely-tapering formation, *f*, to unite with a drop-ornament of the form represented at *g*.

Projecting from the sides of the central stem, A, and body B, are two brackets, C, of square form in their transverse section, being each made up of an incline-shaped upright formation, *h*, with scroll-like upper end, and ball-projection immediately below said end, and uniting at its lower extremity by a curved extension, *i*, with an irregular-shaped formation, *k*, that is mounted by a crowned head, D, and unites, by a curved bar-shaped formation, *l*, through an inverted pyramidal projection, *m*, with a lower side branch jutting from the body B, and made up of a straight portion, *n*, tapering incline, *o*, straight formations, *r* *s*, united by an inverted arch, *t*, having a drop-ornament, *u*, the one, *s*, of said straight formations terminating above in a lip, *v*, that carries the jet and shade-stand.

In parallel relation to the straight portion *n*, tapering incline *o*, and straight formation *r*, of either bracket C, or branch thereof, is a lower similar-shaped bar-like ornament, *w*, united, as at *x*, to the portion *n*, and terminating in a barb or semi-barb-shaped point, *y*.

What I claim as my invention, and desire to secure by Letters Patent, is—

The design for gasaliers, substantially as herein shown and described.

JAMES F. TRAVIS.
